HOIST

Joseph J. Kalmon, Medford, Wis.

Application March 25, 1937, Serial No. 133,076

4 Claims. (Cl. 214—36)

This invention is a hoist, and an object of the invention is to provide a hoist particularly designed for handling a dough trough to the end that the trough may be raised, lowered and tilted 5 for dumping purposes as found desirable and with facility.

The invention together with its objects and advantages will be best understood from a study of the following description taken in connection 10 with the accompanying drawings wherein:—

Figure 1 is a side elevational view of a hoist embodying the features of the present invention.

Figure 2 is a top plan view of the hoist.

Figures 3, 4, and 5 are detail sectional views 15 taken substantially on the lines 3—3, 4—4, and 5—5 respectively of Figure 2.

Figures 6, 7, and 8 are detail sectional views taken substantially on the lines 6—6, 7—7, and 8—8 respectively of Figure 1.

Figure 9 is an end elevational view of a dough trough and

Figure 10 is a fragmentary side elevational view of the dough trough.

Referring to the drawings by reference numerals it will be seen that 6 indicates a rail in the form of an I-beam suspended from a ceiling or other suitable support. Movable along the rail

5 is a carriage 6 that comprises a pair of spaced parallel angle bars 7 secured together at their 20 ends through the medium of U-shaped brackets 8. Brackets 8 are equipped with bearings 9 in which are journaled the axles 10 of bearing equipped flanged rollers 11 that ride on the lower flange of the I-beam rail 5.

An annular track 12 of angle iron is welded or otherwise secured to or made permanent with the lower portion of the brackets 8 at diametrically opposite points on the track.

It will thus be seen that the track 12 will move with the carriage 6 lengthwise of the rail 5.

The track 12 is reinforced through the medium of a pair of spaced parallel angle bars 13, and secured between the angle bars 13 intermediate the ends of said bars is a block 14 through which extends a king pin 15 about which rotates as an axis a hoist frame indicated generally by the reference numeral 16.

The hoist frame 16 comprises a pair of spaced angle bars 17 which intermediate their ends accommodate therebetween a bearing block 18 through which the lower end of the king pin 15 extends as shown in Figure 5.

The hoist frame bars 17 are secured together at their ends through the medium of brackets

in which are journaled the axles 21 of rollers 22 that ride on the annular track 12 as clearly shown. Thus it will be seen that the frame 16 is supported to revolve in the arch of a circle so that said frame is so supported as to be shifted longitudinally relative to the rail 5 and to be rotated in a horizontal plane to any desired position of adjustment.

Suspended from the bars 17 of frame 16 at opposite ends of the latter are bearing arms 23, 10 24 which support a hoisting shaft 25.

On one end of the shaft 25 is a short tubular shaft 26 (see Figure 3) that is equipped at one end with a pulley 27 adapted to accommodate a drive belt or the like whereby drive from a 15 source of power is transmitted to the shaft 26 and through the medium of a clutch device hereinafter more fully referred to to the shaft 25 for driving the latter.

Secured to one end of shaft 25 to rotate therewith is a drum 28 on which is windable a cable 29 that is trained over a sheave 30 suitably mounted on the bale 31 of a dough trough 32 hereinafter more fully referred to. At its free end the cable 29 is secured to the lower end of 25 the bearing member 24 as clearly shown in Figure 1.

Fixed on shaft 26 is a drum 33 on which is windable a cable 34. Cable 34 is also trained over a sheave 35 suitably provided on the aforementioned bale 31 of dough trough 32 and at its free end cable 34 is suitably anchored to the lower end of the bearing member 23 as also shown in Figure 1.

Also mounted on shaft 25 to rotate with said shaft and to slide axially of the shaft is a clutch collar 36 which at one end is provided with pins 37 adapted to be engaged in sockets provided therefor and indicated by the reference numeral 38 and which sockets are provided in one flange 40 of the drum 33. It will thus be seen that when clutch pins 37 are engaged in sockets 38 drive will be transmitted from the shaft 26 to the shaft 25 so that both of the drums 33 and 28 will revolve for winding the cables 34 and 29 thereon or paying out said cables as found desirable for raising or lowering the trough 32.

When, however, it is desired to incline the trough 32 so that the contents of the trough will 50 drain therefrom through an opening provided in one end of the trough clutch 36 is shifted so as to disengage the pins 37 from the sockets 38 with the result that there will be no transmission of

the cable 34 will be wound on the drum 33 to raise one end of the trough 32.

To secure shaft 25 against rotation when it is desired to tilt the trough 32 in the manner just explained there are provided in one end of the clutch collar 36 sockets 39 that engage pins 40 provided on a bearing member 41 suspended from the frame bars 17 in suitable proximity to the bearing member 23.

10 For shifting the clutch collar 36 there is provided a rod 42 that has the opposite ends thereof slidably supported in openings provided therefor in the bearing members 23 and 41. Secured on the rod 42 is the head 43 of a fork 44 that 15 straddles the clutch collar 36 and engages in the groove 45 provided in the periphery of the clutch collar.

A lever 46 is pivoted as at 47 to a horizontal bar 48 that connects the lower ends of the bearing members 23 and 41, and at one end thereof lever 46 has a pin and slot connection 49 with the aforementioned head 43 of fork 44. Suitably connected to the free end of the lever 46 is a pull handle 50. It will thus be seen that by rocking the lever 25 46 in one direction clutch collar 36 will be moved in a direction to engage pins 37 with sockets 38 to place the shaft 25 in driven engagement with the drum 33, while the rocking movement of the lever 46 in an opposite direction will shift the 30 collar 36 in a direction to engage the socket 39 with the pins 40 whereupon clutch collar 36 and shaft 25 are positively secured against rotation.

For securing the clutch collar 36 at either of the two positions mentioned, rod 42 adjacent one 35 end thereof is provided with a pair of spaced notches 52 with which cooperate a spring pressed detent 53 suitably provided as at 54 on the bearing member 41. Thus it will be seen that detent 53 will engage a selected notch 52 as the clutch 40 collar 36 moves to its selected position of adjustment to thereby hold said collar at said position of adjustment.

To secure the suspended trough 32 at the desired position of adjustment there is mounted on 45 the shaft 26 to turn therewith a ratchet wheel 55 with which is cooperable a dog 56 pivoted as at 57 on the bearing member 23 and provided with a pull rod 58.

Also for bracing the annular track 12 relative 50 to the I-beam rail 5 said track 12 has extending inwardly and upwardly from diametrically opposite points thereon braces 59 which at their upper ends are secured to the inwardly directed ends of a U-shaped member 60 that straddles the 55 I-beam rail 5 as shown in Figure 5. At said upper ends of the sides of the U-member 60 and the braces 9 there are provided rollers 61 that have bearing engagement with the chamfered faces 62 provided for the web of the I-beam 5 where 60 said web joins the top flange of the I-beam. At the closed end of the U 60 said U-shaped member 60 is riveted or otherwise secured to the carriage bars 1.

From the foregoing it will be apparent that 65 when it is desired to shift the trough 32 toward either end of the rail 5 carriage 6 is moved along the rail and when it is desired to swing the trough 32 either to the right or left the hoist frame 16 swings about the pivot 15.

70 The trough 32, as previously explained is raised or lowered through the medium of the shaft 25, drums 28 and 33 and cables 29 and 34; while the trough 32 is tilted by winding the cable 34 on the drum 33 to raise one end of the trough.

75 As before mentioned trough 32 is provided at

one end wall thereof with an opening through which the contents of the trough discharges, and for this opening there is provided a door 63 hinged as at 64.

For the door 63 there is provided a latch bolt 5 65 mounted on the door and adapted to engage with a keeper plate 66 mounted on the bottom of the trough 32.

For the bolt 65 there is provided an operating handle 67 made integral with or secured to an intermediate portion of a rod 68 supported in bearings 69 provided therefore on the door 63. The operating handle 67 is connected with the bolt 65 through the medium of a link 70.

At its relatively opposite ends the rod 68 is 15 provided with cranks 71 that engage under keeper lugs 72 provided therefor at opposite sides of the trough in a manner to frictionally retain the shaft 68 against casual rocking movement.

It is thought that a clear understanding of the 20 construction, utility and advantages of an invention of this character will be had without a more detailed description.

Having thus described the invention, what is 25 claimed as new is:—

1. A device for handling dough troughs comprising a rail, a carriage movable along said rail and including an elongated body part, uprights connected with intermediate portions of the body part, an annular track carried by said carriage, brace members connected to diametrically opposite points of the annular track and extending inwardly and upwardly and having their inner ends connected with the upright members of the carriage and rollers carried by 35 the inner ends of said brace members and engaging parts of the rail, a hoist frame mounted to swing in a horizontal plane and equipped with rollers riding on said track, a shaft journaled in said frame, drums on said shaft, a dough 40 trough, and suspension cables for said dough trough windable on said drums.

2. A device for handling dough troughs comprising a rail, a carriage movable along said rail, an annular track carried by said carriage, a 45 bearing block supported at the center of said track, a hoist frame rotatably suspended from said block to swing in a horizontal plane and equipped with rollers riding on said track, a shaft journaled in said frame a drum mounted 50 on said shaft to rotate therewith, a second drum loose on said shaft, driving means connected with said second drum, clutch means for placing the second drum into and out of driving engagement with said shaft, a dough trough, and suspension 55 cables for said dough trough windable on said drums whereby said dough trough may be raised or lowered and one end of said dough trough raised for emptying the dough trough of its contents.

3. A device for handling dough troughs comprising a rail, a carriage movable along said rail, an annular track carried by said carriage, a hoist frame mounted to swing in a horizontal plane and equipped with rollers riding on said track, 65 a shaft journaled in said frame, a drum mounted on said shaft to rotate therewith, a second drum loose on said shaft, driving means connected with said second drum, clutch means for placing the second drum into and out of driving engagement 70 with said shaft, a dough trough, and suspension cables for said dough trough windable on said drums whereby said dough trough may be raised or lowered and one end of said dough trough raised for emptying the dough trough of its con- 75

tents, a ratchet wheel associated with the second drum, and a dog mounted on said frame and engaging said ratchet wheel to secure said second drum against rotation and the dough trough 5 in a desired position of suspension.

4. A device for handling dough troughs comprising a rail, a carriage movable along said rail, an annular track carried by said carriage, a hoist frame mounted to swing in a horizontal plane 10 and equipped with rollers riding on said track, a shaft journaled in said frame, a drum mounted on said shaft to rotate therewith, a second drum loose on said shaft, driving means connected with said second drum, clutch means for placing the 15 second drum into and out of driving engagement

with said shaft, a dough trough, and suspension cables for said dough trough windable on said drums whereby said dough trough may be raised or lowered and one end of said dough trough raised for emptying the dough trough of its contents, a ratchet wheel associated with the second drum, a dog mounted on said frame and engaging said ratchet wheel to secure said second drum against rotation and the dough trough in a desired position of suspension, and operating means 10 for said clutch including means for securing said clutch in either an engaged or disengaged position, optionally. 5
